SHOWER STEP STOOL

George W. Lassen, 834 P Ronda Mendoza,
Laguna Hills, Calif. 92653

Filed Dec. 22, 1969, Ser. No. 20,589

Term of patent 14 years

Int. Cl. D6—01

U.S. Cl. D15—8

FIG. 1 is a perspective view of a shower step stool showing my new design; and

FIG. 2 is a bottom view thereof.

I claim:

The ornamental design for a shower step stool, substantially as shown.
